(57) **CLAIM**

I claim the ornamental design for the canning basket, as shown and described.

DESCRIPTION

FIG. 1 is a perspective view of a canning basket, showing my new design;

FIG. 2 is a top view of the canning basket;

FIG. 3 is a front view of the canning basket, the back view being a mirror image;

FIG. 4 is a left side view of the canning basket, the right side view being a mirror image; and,

FIG. 5 is a bottom view of the canning basket.
